UNITED STATES PATENT OFFICE.

WALENTY WANAT, OF SOUTH MILWAUKEE, WISCONSIN.

GARAGE OR BARN DOOR LOCK.

Application filed April 21, 1927. Serial No. 185,571.

This invention relates to certain new and useful improvements in door locks especially designed for barns and garage doors and has for its primary object to provide a door lock in which the lock mechanism can be operated from the outer side of the door only after the release of a control device on the inner side of the door.

A further object of the invention is to provide a door lock of the above type wherein a plurality of sliding tumblers are engaged with a sliding bolt to hold the latter in a projected and locked condition with devices associated with the tumblers to effect operation thereof for shifting them to releasing positions from either the inner or outer side of the door.

A still further object of the invention is to provide a lock of the above type wherein access to the sliding tumblers from the outer side of the door is controlled by a device operable from the inner side of the door to permit the lock mechanism to be operated from the outer side of the door only when desired.

With the above and other objects in view that will become apparent as the nature of the invention is better understood, the same consists in the novel form, combination and arrangement of parts hereinafter more fully described, shown in the accompanying drawings and claimed.

In the accompanying drawings wherein like reference characters indicate corresponding parts throughout the several views,

Figure 1 is a fragmentary front elevational view of a barn or garage with the vehicle entrance door equipped with the improved lock structure and also illustrating a smaller door equipped with a key operated lock;

Figure 2 is a fragmentary rear elevational view of the door showing the inner face of the lock casing and the device for controlling the insertion of the tumbler operating key into the lock casing at the outer side of the door;

Figure 3 is a fragmentary rear elevational view, similar to Figure 2 with the inner face plate of the lock casing removed, the sliding bolt being illustrated in its projected locking position with the sliding bar tumblers engaged therewith;

Figure 4 is a fragmentary elevational view, similar to Figures 2 and 3 with the locking bolt in its retracted position;

Figure 5 is a similar rear elevational view with the key for operating the sliding tumblers inserted in the lock casing;

Figure 6 is a vertical cross-sectional view taken on line 6—6 of Figure 2;

Figure 7 is a vertical cross-sectional view taken on line 7—7 of Figure 2; and

Figure 8 is a perspective view of the sliding tumbler operating key.

Referring more in detail to the accompanying drawings, in Figure 1 there is illustrated a barn or garage 1 having a vehicle door opening therein closed by the door 2 that is equipped with the improved lock structure 3, while the barn or garage 1 further has a smaller door opening closed by the door 4.

The improved lock structure 3 is shown in detail in Figures 2 to 8 and comprises a rectangular casing 5 set into an opening in the door 2 in a manner as shown in Figure 7 with a removable face plate 6 for the lock casing disposed at the inner side of the door 2.

A sliding lock bolt 7 is mounted in the lower end of the casing 5 and is provided at its upper edge with spaced recesses 8 separated by lugs 9. The nose 10 of the bolt 7 is adapted to be projected through an opening in the end wall of the lock casing 5 for reception in a keeper socket provided in the door frame 11. The opposite end of the sliding bolt 7 extends through the side wall of the casing 5 at the outer side of the door 2 as shown in Figure 1 and is provided with a handle or gripping block 12. As shown in Figures 2 to 7, the open side of the lock casing 5 has an outwardly directed flange 5^a with an arm extension 13 aligned with the bolt 7, the arm extension 13 being provided with a slot 14 through which the rod 15 carried by the handle end of the sliding bolt 7 projects at the inner side of the door. It will therefore be seen that the sliding bolt 7 is operable from the inner side of the door 2 by the knob 15 and is also operable at the outer side of the door by the handle or gripping block 12.

A plurality of sliding tumblers are associated with the upper recessed edge of the sliding bolt 7, the vertically sliding tumbler bars 16 being maintained in spaced relation by the spacer bars 17 secured to the integral face plate of the lock casing 5 as shown in Figures 4, 5 and 7. The sliding tumbler bars 16 are of a width to be received in the

spaced recesses 8 in the sliding bolt 7 when the bolt is projected as shown in Figure 5 to retain the bolt in its projected and locked position. Each sliding tumbler bar 16 carries a handle 18 for manual operation thereof that projects through a registering slotted opening 19 formed in the removable inner face plate 6 of the lock casing 5. When the sliding bolt 7 is fully retracted as shown in Figure 4, the lower ends of the sliding tumbler bars 16 rest upon the upper ends of the spaced lugs 9 at the upper edge of the sliding bolt 7. When the bolt is projected as shown in Figure 5, the sliding tumbler bars 16 gravitationally drop into spaced recesses 8 and retain the bolt in its projected and locked condition. To release the bolt from the inner side of the door 2, a short rod or similar device is simultaneously engaged with all of the handles 18 for elevating the tumbler bars to displace the lower ends thereof from the sliding path of movement of the sliding bolt.

The release of the sliding tumbler bars 16 from the outer side of the door is accomplished by the key or operating bar shown in Figure 8. As shown in Figures 5 and 7, the partition bar 17 has the edge thereof adjacent the closed wall of the lock casing 30 cut away to provide aligned recesses 20 while each sliding tumbler bar 16 is also provided on the corresponding side edge with a recess 21, the recesses 20 and 21 as shown in Figure 5 being aligned with each other when the sliding tumbler bars are lowered into engagement with the sliding bolt 7. The side wall of the lock casing 5 above the handle or gripping block 12, as shown in Figure 6, is provided with an opening 22 aligned with the recesses 20 and 21.

The key bar 23 shown in Figure 8 having a handle 24 upon one end thereof is provided on its upper edge with spaced lugs 25 defining spaced recesses 26 that are inserted through the opening 22 in the lock casing to assume the position shown in Figure 5. It will now be seen that with the key positioned as shown in Figure 5, upward movement of the key will engage the sliding tumbler bars 16 to elevate the same to disengage the lower ends thereof from the sliding bolt 7 and permit the latter to be shifted by the gripping block 12.

A closure plate is associated with the opening 22 in the side wall of the lock casing 5 and its position with respect to said opening is controlled by devices carried by the inner side of the door, the closure plate 27 being limited in its sliding movement 60 by a pin and slot mounting, carries a longitudinally grooved head 28 at the inner end thereof that is exposed at the inner side of the door 2. A bearing block 29 is mounted upon the flange 5^a at the inner side of the door in said groove 28 and has one end of

the latch rod 30 pivotally supported therein. The latch rod 30 is adapted to be moved upwardly on its pivotal support from the position shown in Figure 5 to the position shown in Figure 4 with the intermediate portion thereof received in the grooved head 28 of the plate 27 and with the free end received between the spaced apertured lugs of the keeper 31 with which a retaining pin 32 is associated. It will therefore be seen that when the latch rod 30 is engaged with the keeper 31, sliding movement of the plate 27 with respect to the key entrance opening 22 to the lock casing is prevented.

From the above detailed description of the invention, it is believed that the construction and operation thereof will at once be apparent, it being noted that the sliding bolt 7 is operable from the inner side of the door by simultaneously disengaging the sliding tumbler bars 16 therefrom and shifting the bolt by the knob 15, while the sliding bolt is also operable from the outside of the door by employing the key 23 in the manner above described. When the latch rod 30 is engaged with the keeper 31 as shown in Figure 6 to prevent sliding movement of the closure plate 27 for the opening 22, the lock may still be operated from the inside of the door but operation thereof from the outside of the door is prevented. It is therefore necessary to enter the barn or garage 1 through the small door 4 for disengaging the latch rod 30 from its keeper to permit use of the key 23 from the outer side of the door. When the barn or garage door 2 is locked at night, the latch rod 30 is engaged with the plate head 28, but when the vehicle is removed from the barn or garage during the day time, the latch rod 30 may be disengaged from its keeper 31 to permit operation of the lock mechanism from the outer side of the door.

While there is herein shown and described the preferred embodiment of the present invention, it is nevertheless to be understood that minor changes may be made therein without departing from the spirit and scope of the invention as claimed.

What I claim as new is:

1. In a door lock of the type described, a lock casing set into a door, a sliding lock bolt in the casing, operating means for the bolt at the inner and outer sides of the door, sliding tumbler bars cooperating with the bolt, a handle for each tumbler bar exposed at the inner side of the door, the tumbler bars being operable by a key at the outer side of the door, said casing having an opening for the key and means operable from the inner side of the door to control the entrance to said opening.

2. In a door lock of the type described, a lock casing set into a door, a sliding lock bolt in the casing, operating means for the

- bolt at the inner and outer sides of the door, an opening therein for receiving operating lugs on the key for disengaging the tumblers from the sliding bolt. 40
- 5 5. In a door lock of the type described, a lock casing set into a door, a sliding lock bolt in the casing, operating means for the bolt at the inner and outer sides of the door, sliding tumbler bars cooperating with the bolt, a handle for each tumbler bar exposed at the inner side of the door, the tumbler bars being operable by a key at the outer side of the door, said casing having an opening for the key, a closure plate for the opening, and means operable from the inner side of the door for controlling the position of the 10 plate relative to the opening. 45
- 15 3. In a door lock of the type described, a lock casing set into a door, a sliding lock bolt in the casing, operating means for the bolt at the inner and outer sides of the door, sliding tumbler bars cooperating with the bolt, a handle for each tumbler bar exposed at the inner side of the door, the tumbler bars being operable by a key at the outer side of the door, said casing having an opening for the key, a closure plate for the opening, and means operable from the inner side of the door for controlling the position of the 20 plate relative to the opening, apertured spacing bars for the tumblers, each of said tumblers having an opening therein for receiving operating lugs on the key for disengaging the tumblers from the sliding bolt. 50
- 25 4. In a door lock of the type described, a lock casing set into a door, a sliding lock bolt in the casing, operating means for the bolt at the inner and outer sides of the door, sliding tumbler bars cooperating with the bolt, a handle for each tumbler bar exposed at the inner side of the door, the tumbler bars being operable by a key at the outer side of the door, said casing having an opening for the key and means operable from the 30 inner side of the door to control the entrance to said opening, apertured spacing bars for the tumblers, each of said tumblers having 55
- 35

6. In a door lock of the type described, a lock casing set into a door, a sliding lock bolt in the casing, operating means for the bolt at the inner and outer sides of the door, sliding tumbler bars cooperating with the bolt, a handle for each tumbler bar exposed at the inner side of the door, the tumbler bars being operable by a key at the outer side of the door, said casing having an opening for the key, a closure for the opening, a head at the inner end of the closure plate and a latch rod movable to a position to overlie the head to hold the closure plate in closing relation 60 with respect to the opening. 65

In testimony whereof I affix my signature.

WALENTY WANAT.
